UNITED STATES PATENT OFFICE.

FRED M. CARR, OF WINCHESTER, MASSACHUSETTS.

DESIGN FOR A METAL STRIP.

Application filed February 12, 1925. Serial No. 12,361. Term of patent 3½ years.

To all whom it may concern:

Be it known that I, FRED M. CARR, a citizen of the United States, residing in Winchester, in the county of Middlesex and Commonwealth of Massachusetts, have invented a new, original, and ornamental Design for Metal Strips, of which the following is a specification, reference being had to the accompanying drawing, forming part thereof.

Fig. 1 of the drawing is a plan view of a metal strip showing my new design, and

Fig. 2 is a section on line 2—2 of Fig. 1. The strip as illustrated is intended for use in forming in part metallic frames, for embracing and supporting dishes of glass or other material and for attachment to metal containers to form ornamental bands or borders thereon.

I claim:

The ornamental design for a metal strip, as shown.

FRED M. CARR.
